UNITED STATES PATENT OFFICE.

EDWARD WILSON, OF ST. LOUIS, MISSOURI, ASSIGNOR TO WILSON ENGINEERING COMPANY, OF ST. LOUIS, MISSOURI, A CORPORATION OF MISSOURI.

COMPRESSOR.

Application filed April 9, 1921. Serial No. 459,944.

To all whom it may concern:—

Be it known that I, EDWARD WILSON, a citizen of the United States, residing at St. Louis, Missouri, have invented a new and useful Compressor, of which the following is a specification.

This invention relates to compressors.

An object of the invention is to provide a compressor of novel and simplified construction, whereby the operative mechanism of the compressor is certainly maintained in a condition of highest efficiency and whereby the operative parts automatically retain proper relative adjustment during the operation of the compressor.

Another object of the invention is to provide a novel system of lubrication for the operative mechanism of the compressor.

Another object of the invention is to provide an oscillating piston shaft of a compressor with distinctively novel and efficient means for supporting the same in proper relative position, and for permitting the mechanism driven thereby to maintain proper relationship as to all parts.

Another object of the invention is to provide a compressor which is compact and in which the operating mechanism is enclosed within a stationary support and immersed in oil, the operative parts being properly constructed and arranged to permit the oil to maintain perfect lubrication.

Various other objects of the invention and numerous advantages obtained thereby will be made apparent by the following description, reference being made to the drawings in which—

Fig. 1 is a view, partly in section, showing many of the novel features of the invention.

Fig. 2 is a cross sectional view approximately on the line 2—2 of Fig. 1.

Fig. 3 is a sectional view on the line 3—3 of Fig. 1.

Fig. 4 is a view showing other features of the invention, the oscillating piston shaft being shown in section and the combined bushing and thrust member being in elevation.

The compressor comprising my present invention is a compact and self-contained structure in which the operative mechanism is preferably enclosed within a stationary case mounted upon a supporting base. The operative mechanism of the compressor is

driven by a motor which may be included as an integral part of the machine, as shown.

As shown, the base 1 constitutes the support for the compressor and the motor 2. The motor 2 is mounted on the base 1 and is arranged to operate the operative mechanism of the compressor by proper connections. A desirable form of such connections for operating the compressor from the motor is shown.

In the form shown the connections from the motor to the operating mechanism of the compressor includes a fly wheel 3 enclosed within a part 4 of the case of the machine. The part 4 of the machine case connects with the motor case at one end and is united with the compressor case proper at the opposite end so as to obtain the desired rigidity of the connected parts.

A wall 5 in connection with the case has a cylindrical extension 6 supporting anti-friction bearings 7 in which the hub of the fly wheel 3 is journaled for rotation. The hub of the fly wheel 3 is mounted on a bushing 8 which is keyed to the shaft of the motor by a key 9. The fly wheel is held rigid with the bushing and the bushing is rigid with the motor shaft.

A wrist pin 10 extends from the bushing 8 eccentrically with respect to the axis of the motor shaft. The wrist pin 10 constitutes a support for an anti-friction bearing 11 upon which an arm 12 is mounted for rotation.

The part of the case or housing of the compressor which encloses the compressor mechanism includes a stationary housing 13 rigidly mounted on the base 1. A non-rotative supporting cylinder 14 is within the housing 13. As shown, the cylinder 14 is rigid with the housing and is incapable of any movement relative thereto. A non-rotative cylinder 15 is mounted within the cylinder 14 and is held from rotation by keys 16 which, however, permit axial movement of the cylinder 15 within the supporting cylinder 14 in order to maintain perfect adjustment of the parts and to permit the parts to be adjusted in accommodation to each other. The cylinder 15 is provided with one or more compression chambers, said compression chambers being formed by inwardly extending sectors 17 (Fig. 3) whose inner ends contact with the rocking piston shaft 18. One end of the piston shaft 18 is journaled for

rocking movements in an anti-friction bearing 19 at the outer end of the housing 13, while the opposite end of said shaft 18 is journaled for rocking movements in an anti-friction bearing 20 in the opposite end of the housing 13. As shown, the axis of the shaft 18 is a greater distance from the plane of the axes of the motor shaft 8 and of the fly wheel 3 than is the wrist pin 10, though 10 this arrangement may be otherwise if desired.

As shown, the interior of the cylinder 15 is divided into two compression chambers by the sectors 17. The piston comprises sectors 21 integral with the rock shaft 18 arranged to operate within the compression chambers in the cylinder 15.

As shown, the shaft 18 has a passage 22 arranged to receive the air from an air chamber 23 to which the air is admitted through an inlet 24. The means for controlling admission of air from the passage 22 to the compression chambers may be of any desired construction and arrangement 25 such, for instance, as that disclosed in my companion application Serial No. 424,034, but since such controlling means is not specifically claimed herein the same is not shown or described in detail. So, also, the 30 means for controlling the outlet passages 25 which go through the sectors 17 is not specifically shown herein, that shown in my said companion application being satisfactory. The passages 25 open into a circumferential 35 chamber 26 around the cylinder 15 and within the cylinder 14. From the chamber 26 the compressed air passes into the housing 13 through appropriate openings 27 provided for that purpose; and from the housing 13 40 the compressed air is taken to any desired point of use through a passage 28.

It will be seen by reference to Figs. 1 and 2 that the working parts within the housing 13 are immersed in oil. The level of the oil 45 is below the openings 27 so that no material quantities of the oil will be caused to enter the chamber 26 through the openings 27. Such small quantities of the oil as work through the operative parts and into the 50 compression chambers of the machine will be forced out as an incident to operation of compression and into the chamber 26. The oil received within the chamber 26 will be carried therefrom by the movement of the 55 compressed air and returned to the housing 13. An oil gage 29 may be provided in connection with the machine so that the depth of the oil may be observed.

The walls of the ends of the compression 60 chambers which are in the cylinder 15 are of novel and improved construction and arrangement in this compressor. The wall 30 at the outer end of said compression chambers is formed with a hub 31 and is keyed 65 to the shaft 18. Thus, while the cylinder 15

is held from rotation or rocking, the end wall 30 thereof rocks with the shaft 18 thereby subjecting the contacting surfaces to lapping and adjustment movements. The outer end of the shaft 18 extends through the end wall of the cylindrical member 32 which communicates with the air receiving chamber 23. A nut 33 screws onto the end of the shaft 18 and clamps the end of the cylindrical member 32 against the inner ring of the anti-friction bearing 19 which is also abutted against the end wall 30. The cylindrical member 32 is formed with a number of circumferential grooves 34 adapted to receive oil that works from the housing 13 through the operative parts. In practice it has been found that a sufficient quantity of oil will work into and through the bearings to maintain proper lubrication. The spring 35 may be mounted to exert pressure against the outer end of the bearing so as to press the end wall 30 into contact with the end of the cylinder 15. In some cases the spring 35 will not be needed and I contemplate the omission of such spring wherever its presence will not be useful. In any case the spring is needed only to balance the pressure at the opposite end of the machine and, since such pressure becomes balanced when the machine is placed in operation, the spring is needed in any case only at the starting of the machine.

The wall 36 at the end of the compression cylinder opposite from the wall 30 is keyed to the shaft 18 and rocks with said shaft as does the wall 30. The wall 36 is in the form of a thrust member having a flange 37 arranged to operate against the part 38 in which the hub of the wall thrust member is mounted for rocking movements. A number 105 of holes 39 (Figs. 1 to 4) open through the flange 37 into a circumferential groove or chamber 40 in the face of the flange 37 that operates against the part 38. This permits oil from the housing 13 to pass into the 110 groove or chamber 40. The oil works from the groove or chamber 40 between the operating parts, keeping them in a lubricated condition, and filling the grooves 41 around the hub of the wall thrust member within the 115 supporting part 38. The use of this construction eliminates the need for a stuffing box.

From the foregoing it will be seen that the piston, including the sectors 21, is mounted 120 for rocking movements within the stationary cylinder 15. Such rocking movements are imparted by the driving connections from the motor, part of which has already been described, including the arm 12 which is 125 supported eccentrically relative to the axis of the motor shaft. An arm 42 is attached to the end of the shaft 18 and has its end overlapping the end of the arm 12. The arms 12 and 42 are pivotally united by an 130

anti-friction pivot connection 43 (Fig. 2). As a result of this construction a rocking movement is imparted to the shaft 18 by the continuous rotation of the motor shaft in one direction. It will be seen that the support 10 for the arm 12 rotates around the plane of the axis of the shaft 18 and that, as a result of the novel arrangement and construction shown and described, a rocking movement is imparted to the shaft 18 and thereby to the pistons 21 by such rotary movement of the arm 12.

The described or equivalent means for obtaining the results disclosed constitute important features of the present invention. My invention accomplishes all of its intended objects and variations may be made in the construction and arrangement of the parts without departure from the scope and nature of the invention. I do not restrict myself to unessential features, nor otherwise, except as set forth in the appended claims.

What I claim and desire to secure by Letters Patent, is:—

- 25 1. A compressor, comprising a housing, a stationary cylinder within the housing, a non-rotative cylinder supported within the stationary cylinder and being capable of axial movement therein, a rocking piston within the non-rotative cylinder, end walls for the non-rotative cylinder arranged to rock with the piston, a shaft for operating said piston, a power driven shaft supported out of alinement with the piston shaft, and connections from the power driven shaft to the piston shaft for imparting rocking movements to the piston shaft by the continuous rotation of the power driven shaft in one direction.
- 30 2. A compressor, comprising a housing arranged to contain oil and to receive compression above the level of the oil, a non-rotative cylinder below the level of the oil in the housing, compression chambers within the cylinder, pistons arranged to operate within said chambers, a rock shaft for rocking said pistons, end walls for the cylinder arranged to rock with said rock shaft, a rotary motor shaft, and connections operated by the motor shaft for imparting rocking movements to the piston shaft by the continuous rotation of the motor shaft in one direction.
- 35 3. A compressor, comprising a stationary housing arranged to contain oil and to receive compression above the level of the oil, an axially adjustable non-rotative cylinder within the housing, compression chambers in said cylinder, pistons arranged to operate within the compression chambers of the cylinder, mechanism for rocking said pistons, end walls for the compression chambers in the cylinder, and means for moving the end walls with the pistons.
- 40 4. A compressor, comprising a stationary housing arranged to contain oil in the bottom portion thereof, and to receive compression above the level of the oil, a stationary cylinder in the housing, a non-rotative cylinder supported within the stationary cylinder and being capable of axial adjustment relative thereto, a chamber in the stationary cylinder arranged to receive compression from the non-rotative cylinder and opening into the housing above the level of the oil, compression pistons within the non-rotative cylinder, and mechanism for operating the compression pistons.
- 45 5. A compressor, comprising a stationary housing arranged to contain oil in the bottom portion thereof, and to receive compression above the level of the oil, a stationary cylinder within the housing, a non-rotative cylinder within the stationary cylinder below the level of the oil, a chamber below the level of the oil arranged to receive compression from the non-rotative cylinder and opening into the housing above the level of the oil, a piston shaft extending through the non-rotative cylinder, pistons in connection with said shaft, end walls supported by the shaft and arranged to move therewith relative to the non-rotative cylinder, a power shaft supported out of alinement with the piston shaft, and mechanism for rocking the piston shaft by the continuous rotation of the power shaft in one direction.
- 50 6. A compressor, comprising a housing, a cylinder within the housing, compression chambers in said cylinder, a piston shaft supported for rocking movements, pistons on said shaft arranged to operate within said chambers, end thrust walls for said cylinder, and means for rocking said walls with the piston shaft.
- 55 7. A compressor, comprising compression chambers, a piston shaft, pistons arranged to operate within said compression chambers, end walls for the compression chambers keyed to the piston shaft, anti-friction bearings for said shaft, and means including said anti-friction bearings for holding the end walls in position to close the ends of the compression chambers.
- 60 8. A compressor, comprising a motor, a rotary shaft driven by the motor, a piston shaft, pistons on said piston shaft, compression chambers within which said pistons operate, end walls for the compression chambers arranged to operate with the piston shaft, means for holding the end walls in position to close the ends of the compression chambers, and connections from the rotary shaft to the piston shaft for imparting rocking movements to the piston shaft by the continuous rotation of the rotary shaft in one direction.
- 65 9. In a compressor, the combination with a rocking piston shaft, of a motor, a rotary shaft driven by said motor, a support in

connection with the rotary shaft, an arm pivoted on said support eccentrically on the axis of the rotary shaft, an arm attached to the rocking piston shaft, and an anti-friction connection between said arms for imparting rocking movements to said piston shaft by the continuous rotation of said rotary shaft in one direction.

10. A compressor, comprising a stationary housing, a cylinder rigid within the housing, a non-rotative axially adjustable cylinder in the rigid cylinder, a chamber within the rigid cylinder, piston chambers in the axially adjustable cylinder, a piston shaft, pistons on said shaft arranged to operate in said chambers, means for rocking said piston shaft to operate said pistons, and end walls for said piston chambers supported by and arranged to rock with said piston shaft.

11. A compressor, comprising a stationary housing, a cylinder rigid within the housing, a non-rotative axially adjustable cylinder in the rigid cylinder, a chamber within the rigid cylinder, piston chambers in the axially adjustable cylinder, a piston shaft, pistons on said shaft arranged to operate in said chambers, means for rocking said piston shaft to operate said pistons, end walls for said piston chambers supported by and arranged to rock with said piston shaft, anti-friction bearings for said piston shaft, and means including said anti-friction bearings for holding said end walls thrust against the 35 end of the axially adjustable cylinder to close the ends of the chambers therein.

12. A compressor, comprising a stationary housing arranged to contain oil in the lower portion thereof and to receive compression 40 therein above the level of the oil, a non-rotative axially adjustable cylinder supported within the housing below the level of the oil, compression chambers in said cylinder, mechanism for effecting compression in the 45 compression chambers of the cylinder, and means for discharging the compression from the compression chambers in the housing above the level of the oil.

13. A compressor, comprising a stationary housing arranged to contain oil in the lower portion thereof, a non-rotative cylinder sup-

ported within the housing below the level of the oil, compression chambers in said cylinder, a piston shaft extending through the cylinder, pistons on said shaft within the compression chambers, end walls closing the ends of the compression chambers immersed within the oil, mechanism for rocking the piston shaft, and means for rocking the end walls with the piston shaft.

14. A compressor, comprising a stationary cylinder, a non-rotative cylinder supported for axial movement and adjustment in the stationary cylinder, compression chambers within the second cylinder, a piston shaft extending through the second cylinder, mechanism for rocking the piston shaft, means for rocking the end walls with the piston shaft, and pistons on the piston shaft within the second cylinder.

15. A compressor, comprising a stationary cylinder, a non-rotative cylinder supported for axial movement and adjustment in the stationary cylinder, compression chambers within the second cylinder, a piston shaft extending through the second cylinder, mechanism for rocking the piston shaft, means for rocking the end walls with the piston shaft, pistons on the piston shaft within the second cylinder, anti-friction bearings supporting the piston shaft, and means including the anti-friction bearings for holding the end walls thrust against the ends of the second cylinder to close the ends of the compression chambers.

16. A compressor, comprising a rigid cylinder, a compression cylinder within the rigid cylinder, means holding the compression cylinder from rotating and permitting axial adjustment thereof in the rigid cylinder, a piston shaft extending through the compression cylinder, a power shaft, means for imparting rocking movements to the piston shaft by the continuous rotation of the power shaft in one direction, end walls for the compression cylinder arranged to rock with the piston shaft, anti-friction bearings for the piston shaft, and means including the anti-friction bearings for holding the end walls thrust against the ends of the compression cylinder.

EDWARD WILSON.
